UNITED STATES PATENT OFFICE.

FRED A. ALMY, OF SEATTLE, WASHINGTON.

ROTARY ENGINE.

1,088,391.

Specification of Letters Patent.

Patented Feb. 24, 1914.

Application filed December 30, 1905. Serial No. 293,590.

To all whom it may concern:

Be it known that I, FRED A. ALMY, a citizen of the United States, residing at Seattle, in the county of King and State of Washington, have invented a new and useful Rotary Engine, of which the following is a clear and concise specification.

My invention relates to a new and useful improvement in rotary engines and more particularly to engines first operating on the impulse of an explosion of gas and having for the next impulse the steam generated by the heat of the gas thus causing the engine to operate alternately on steam and gas.

The objects of my invention are to provide an engine alternately operating on the impulse of the explosion of gas and with the admission of steam within the cylinder; to provide an engine in which a portion of the heat of combustion therein may be used to generate steam and to automatically regulate the water to take up the heat within the walls of the combustion chamber and walls of the piston chamber.

These objects are accomplished by the construction hereinafter more fully set forth and succinctly pointed out in the appended claims.

In the drawings Figure 1 is a vertical section of my device taken on the line $x-x$ shown in Fig. 3 and viewed in the direction indicated by the arrow below said figure. Fig. 2 is an elevation of my device in which a portion of the fly wheel is broken away. Fig. 3 is a plan view in which a portion of the fly wheel is broken away and shown in section to illustrate the cam race in the web of said fly wheel. Fig. 4 is a vertical longitudinal section of my device taken on the lines Z-Z viewed in the direction of the arrow shown in Fig. 1, Fig. 5 is a fragmentary elevation of the upper part of the engine with the time valve and gas intake or check valve partly in section showing in dotted and full lines the position of the cam and levers for opening the time valve. Fig. 6 is a fragmentary view of the fly wheel illustrating in detail the cam race which operates the abutment. Fig. 7 is a detail view of the thermostat for regulating the flow of water to be admitted to the gas explosion, steam generating and expansion chamber of my device. Fig. 8 is a

transverse section of the oscillating time valve which controls the admission of the water and lubricant admitted through the gas explosion, steam generating and expansion chamber.

Similar reference characters refer to similar parts throughout the several views of my device as illustrated in the accompanying drawings.

I have provided a body or cylinder (A) having at its lower extremity the base or bed plate (a). The body (A) is irregular in shape, both upon the interior and exterior which may be understood by referring to the drawing. The top part (B) of said body (A) may be removed for the purpose of repairing the parts within said body (A) and is secured to said body by the bolts (b). The piston or impelling chamber (C) is formed in the lower part of said body (A) which is provided with cylinder heads (D) which are extended to also cover the top portion (B) of my device and are secured to the portions (A) and (B) by the bolts (c). By this construction and inclosed within the body (A) and cylinder heads (D) are formed three chambers which will be hereinafter more fully set forth.

I have provided a main shaft 1 which passes centrally and longitudinally through the piston chamber (C) and also through the cylinder heads (D) which main shaft is rigidly secured to the piston wing (2) shaped substantially as shown in the accompanying drawings, said piston wing 2 co-acting with an abutment which is preferably formed integral with the shaft 3 affording a means whereby power may be applied within said piston chamber (C) on the main shaft (1). The abutment 4 is provided with a neck 5 having a lower face 6 resting on the periphery of the shaft 1, and conforming to the periphery thereof, said abutment is also provided with a face 7 at the lower extremity thereof which is adapted to engage the face 8 of said piston wing 2 when the projecting neck 5 is advancing toward said shaft 1.

By referring to the drawings it will be seen that the oscillating abutment is of a peculiar shape and has, in addition to the neck 5, the face 7 as well as the concave face (d) and the convex faces (e), (f), (g) and (h). In Fig. 1 the oscillating abut-

ment 4 is shown in its lowest position, the face 6 resting upon the shaft and the face 7 resting against the surface 8. The weight of the abutment is supported by means of 5 the crank arm 9 which is provided with an outwardly projecting finger 10 adapted to travel within the cam race 11. The cam race 11 is preferably provided on the inner surface of the solid web of the fly wheel (E) 10 and by referring to Fig. 6 of the accompanying drawings the two positions of the finger 10 may be understood, the full lines representing the finger in the lowermost position, the abutment in this position resting against 15 the shaft 1 while the dotted lines illustrate the raised position of the finger which also carries the abutment to its raised position.

Communicating with the intake or check valve (H') is a passageway 12 through 20 which is allowed to pass a sufficient quantity of gas to make a charge, which gas is delivered to the compression chamber (I) when the abutment 4 descends. The suction within the compression chamber (I) when the 25 abutment descends opens the valve passage (H') by drawing the valve stem head 13 to the position disclosed in dotted lines in Fig. 5 of the accompanying drawings. It is to be understood that the opening of the valve 30 (G') to the intake valve (H') takes place at each alternate revolution which is accomplished by a head 15 provided on the valve stem 14 co-acting with levers and a cam hereinafter described. The operation of the 35 gas time valve (G') provided in the gas supply pipe (F) which leads to the carbureter, and the oscillating valve for admitting water into the gas explosion, steam generating and expansion chamber (J) is as follows. I have provided the pinion 16 secured to the shaft 1, said pinion meshing with the gear 17 which is of twice the pitch 40 diameter and loosely mounted on the stud 18 secured to one of said cylinder heads (D) which can be readily understood by referring to Figs. 4 and 2 of the accompanying 45 drawings. I have provided a cam 19 which is preferably rigidly secured to said gear 17 and shaped substantially as illustrated in Fig. 5. I have provided a finger 20 which 50 is held against the periphery of said cam 19 by the spring 31 which rests against the crank arm 21 to which said finger is secured, and said crank arm 21 is rigidly secured to the time valve 22, in which are 55 formed the water passageways 23 and lubricant passageway 24, said passageways 23 and 24 registering with the passageways 25 and 26 respectively when said crank arm 21 60 is in the position as disclosed in the dotted lines in Fig. 5 allowing the water and lubricant to enter the gas explosion, steam generating and expansion chamber. When the 65 full lines in Fig. 5 and dotted lines in Fig.

2, the passageways 23 and 24 register with the passageways 27 and 28 respectively. The passageway 27 communicates with the water supply pipe 29 which furnishes the water to be generated into steam at each alternate revolution of the piston. 70

It is obvious that the gear wheel 17 makes one revolution to each two revolutions of the gear 16, thus the cam 19 will hold the crank arm 21 in a vertical position for one revolution and hold the oscillating time valve 22 in a closed position which prevents any water from passing through the cylinder of the engine while the explosion of gas is taking place also checking the gas from passing 80 into the valve 22. The crank arm 21 will instantaneously upon the second revolution of said gear 16, take the position illustrated in dotted lines in Fig. 5 by reason of the spring 31 as before stated keeping the projecting finger 20 in contact with the cam 19. This operation permits the water within the passageway 23 as well as the lubricant to 85 gravitate into the gas explosion steam generating and expansion chamber (J) and further opens the time valve (G') which admits gas to pass through the valve (H'). The expansion chamber (J) having been heated by the alternate explosion of gases therein causes the water when entering said chamber 90 (J) which is highly heated, to be almost instantaneously converted into steam at high pressure which produces the second power stroke. 95

When the crank arm 21 changes to the position disclosed in dotted lines in Fig. 5 the lever 32 is forced thereby into the position also indicated in dotted lines thus actuating the bell crank 33 which is pivotally held by means of the brackets (i) secured to the portion (B), said bell crank opening the time valve (G') by raising the valve head 15 from its seat 12 which allows a flow of gas through the check valve (H') when the pressure is released in the chamber (I). Said portion (B) is provided with a by-pass 34 which communicates with the gas explosion steam generating chamber (J) after passing through the check valve 35. Spaced 100 at a suitable distance apart and at each side of this by-pass 34 are the passages or openings 36 which place the expansion chamber (J) in communication with the atmosphere at the top surface of the part (B). Secured to the top part (B) and within the explosion chamber (J) I have provided a thermostat (K) comprising a piece of brass 36' substantially of the shape and form shown and having a piece of untempered steel spring 37 secured thereto. The difference in expansion between the brass and steel when heat or cold is applied imparts motion to a link 39 secured at the upper curved end 38 of the brass 36'. Said link is secured to the arm 40 which is secured to the shaft 41 105 110 115 120 125 130

which passes through one of the cylinder heads (D) and is provided at its end with the grooved cam 42. Thus when the thermostat is heated and expands due to the temperature within the gas explosion chamber (J), said cam 42 will be partially oscillated or rotated as the groove thereon is angularly disposed relative to the longitudinal axis of said cam. The projection 44 which travels 10 therein will force a water regulator stem 43 to travel longitudinally regulating the water in the passageway 23, the lubricant being regulated by the screw plug 46 as clearly shown in Fig. 4.

15 As noted heretofore the engine compresses the gas each alternate revolution and the explosion takes place each alternate revolution. The piston 2 will thus be revolved by the explosion until exhausting the burnt gas 20 through the opening (L) after which the abutment is raised and as no gas is admitted by the mechanically operated valve (G) no fresh mixture will be admitted and the abutment will reverse its motion and travel 25 downwardly forming a partial vacuum in the chamber (I) and if no steam is formed by admitting water before the partial vacuum takes place, air will be admitted as long as there is a tendency to produce a vacuum 30 in the combustion chamber (J). It will be seen at each alternate revolution that if no fuel is admitted through the valve 13 and through the valve 35 into the explosion chamber (J') and if no steam is generated in 35 said explosion chamber, a partial vacuum will be formed which will draw air through the openings 36 and through the check valves 35'.

The air inlets 36 assist in scavenging the 40 cylinder by admitting a current of air and also release the partial vacuum formed during the rotation of the piston. I have provided an exhaust port (L) which is disposed near the end of the stroke or sweep of the 45 piston wing 2, said piston wing 2 raising the abutment 4 and compressing the gases within the chamber (I), said gases having been admitted by the suction produced on the downward movement of said abutment 4 50 through the intake valve passage (H'). The abutment 4 is assisted in its travel by the cam-way or groove 11 provided on the web of the fly-wheel as may be seen by referring to Fig. 6, said abutment is also assisted in its 55 movement by the projection 5 traveling on the surface of the piston wing 2. The arm 9 and projection 10 co-act with the said groove or cam-way 11 in raising and lowering said abutment, said arm 9 being secured 60 to the shaft 3 of said abutment. It will be noticed that the general shape of the cam-way 11 resembles the shape of said piston wing 2 and travels in fixed relation thereto. The gas is received and compressed within 65 the gas explosion, steam generating and ex-

pansion chamber (J) after having been admitted through the by-pass 34 aforesaid. The spark plug 47 which ignites the charge of gas at every alternate revolution of the piston is also provided in said chamber (J) 70 which is closed by the neck 5 when the abutment is in its upper position as may be seen by dotted lines in Fig. 1. When the abutment 4 is in the lower position said expansion chamber (J) communicates with the piston chamber (C) by means of a passage (M).

The operation of my device is substantially as follows: It is first necessary to start the engine by cranking in the usual way common to starting an internal combustion engine. The first 45 degrees of the travel of the piston wing 2 a suction is produced in which a fresh charge of gas is taken into the compression chamber (I) from the carbureter through the check valve passage (H'). The air passages 36 admit air from the time the abutment 4 begins to descend throughout the remaining 270 degrees of the cycle after which compression of gas in the chamber (I) occurs said gas being forced into the explosion chamber (J) through the by-pass 34. The second revolution is different from the first. As the oscillating abutment 4 descends, gas is admitted from the carbureter compressed, and ignited in the usual manner, the expansion of which 95 revolves the piston wing substantially 270 degrees at which point the gases exhaust. It will be seen by referring to the drawings and as hereinbefore stated that the cam 19 makes a revolution for each two revolutions made by the piston wing which in view of the peculiar shape of said cam, causes the gas to be admitted every alternate revolution of said piston and permits water and lubricant to be admitted in the chamber J, which by reason of the heat from the explosion during the previous revolution causes the water to be evaporated forming 100 steam which on the downward movement of the abutment is admitted within the piston chamber and therefore impelling the piston wing for 270 degrees, the steam then being exhausted. The action of the high pressure 105 steam which has been generated within the chamber (J) assists the downward travel of the abutment acting on the neck 5 until said neck has traveled sufficiently downward to have opened the port (M). During the remaining 90 degrees of travel of the piston wing a new charge of gas is admitted to the explosion chamber (J) after having been compressed by the upward movement of the abutment in the compression chamber I, 110 after which said gas is admitted into the cylinder and exploded as before. Thus 115 steam is generated at each alternate revolution and the explosion of gas takes place within the piston chamber alternately with 120 the gas explosion, steam generating and ex- 125

the admission of the steam which is generated by the heat stored within the walls of the engine at the time of explosion. The admission of the water is regulated by the 5 temperature within the chamber (J) which acts upon the thermostat (K) which operates the valve 43 as hereinbefore stated. Thus the exact quantity of water is admitted to generate steam which takes up the heat 10 stored within the walls of my device. It is obvious that the chamber (J) will be cold at the time of starting the engine and that the thermostat will not permit water to enter until sufficient heat has been stored to evaporate 15 all of the water.

I have provided an oil cup or reservoir 30 adapted to supply the combustion chamber of my device with the proper quantity of oil.

Having thus described my invention what 20 I claim as new and desire to secure by Letters Patent is:

1. In a rotary engine, a piston chamber, a piston wing traveling therein, an abutment and a neck formed on said abutment operating 25 in contact with said piston wing, a compression chamber formed behind said abutment and means for supplying gas to said compression chamber, said abutment compressing said gas when raised, an explosion 30 chamber closed by the neck of said

abutment when raised and communicating with said compression chamber through a passage and a check valve in said passage.

2. In a rotary engine, a piston chamber, a piston wing traveling therein, an abutment 35 and a neck formed on said abutment operating in contact with said piston wing, a compression chamber formed behind said abutment and means for supplying gas to said compression chamber, said abutment compressing said gas when raised, an explosion 40 chamber closed by the neck of said abutment when raised and communicating with said compression chamber, and a thermostat provided in said explosion chamber and a 45 water supply valve connected to said explosion chamber and controlled by said thermostat whereby the quantity of water supplied to said explosion chamber is automatically regulated therein, the heated walls 50 of said explosion chamber evaporating the water supplied thereto whereby steam is generated in said explosion chamber each alternate revolution of said piston.

In testimony whereof I affix my signature 55 in presence of two witnesses.

FRED A. ALMY.
